UNITED STATES PATENT OFFICE

134,501

DESIGN FOR A CLOCK

Chester William Boehmer, Kitchener, Ontario,
Canada

Application June 11, 1941, Serial No. 101,406

Term of patent 3½ years

To all whom it may concern:

Be it known that I, Chester William Boehmer, a subject of the King of Great Britain, residing at the city of Kitchener, in the county of Waterloo, in the Province of Ontario, Dominion of Canada, have invented a new, original, and ornamental Design for a Clock, of which the following is a specification, reference being had to the accompanying drawing, forming part thereof.

Fig. 1 is a front elevation of the clock, showing my new design;

Fig. 2 is a side elevation; and

Fig. 3 is a top plan view thereof.

My design for a clock of the configuration as shown is characterized by the placement of the wide hoop-like elements, the two at the top overlapping on the left and the two at the bottom overlapping on the right of the face of the clock, the overlapping portions being ornamented by stud-like elements, said hoops being arranged at predetermined levels so as to form mountings for the numerals 10, 2, 8, and 4.

I claim:

The ornamental design for a clock, as shown and described.

CHESTER WILLIAM BOEHMER.
